Fernando Forés, INVENTOR

BY Victor J. Evans

ATTORNEY

UNITED STATES PATENT OFFICE

FERNANDO FORTÉS, OF MANILA, PHILIPPINE ISLANDS

NOSTRIL INSERT

Application filed April 14, 1930. Serial No. 444,296.

This invention relates to certain new and useful improvements in medical appliances primarily designed for application and use within the nostrils.

5 One of the principal objects of the invention resides in the provision and arrangement of a supporting structure for the appliances designed for engagement with appropriate portions of the nostrils in such 10 manner that the wearer may inhale and exhale freely.

Another object of the invention consists of strainer elements positioned within the supporting structure to filter the air 15 breathed by the wearer.

More specifically stated the strainer elements and supporting structure are so disposed as to prevent injury and to afford comfort to the wearer and yet preserve the 20 natural shape of the nose.

With the above and other objects in view, the invention further consists of the following novel features and details of construction, to be hereinafter more fully described, 25 illustrated in the accompanying drawings and pointed out in the appended claim.

In the drawings:—

Figure 1 is a top plan view of the invention.

30 Figure 2 is a bottom plan view thereof.

Figure 3 is a longitudinal sectional view taken on line 3—3 of Figure 2.

Figure 4 is a view similar to Figure 3 taken through a modified form of the invention.

Referring to the drawings in detail wherein like characters of reference denote corresponding parts, the reference character 10 indicates generally an annular form of 40 band or rim shaped in conformity with the natural contour of nostril passages. As best shown in Figure 3 of the drawings, the rim 10 is downwardly and inwardly tapered to prevent displacement thereof and to prevent 45 injury or discomfort to the wearer's nose. A companion rim 11 threadedly engaged with the inner side wall of the rim 10 is provided with an inwardly projecting annular ledge 12, the purpose and advantage 50 of which will be presently apparent.

It is also my purpose to provide means for the filtering purification and straining of the air breathed by the wearer whereby persons affected with hay fever and laborers employed in places where their line of work 55 is about machinery and the like where the air is filled with flying or floating particles, which if breathed might prove detrimental to his health.

The strainers comprise one such as indicated at 13, preferably formed of fine mesh wire or other reticulated material arranged in disk formation and seated peripherally thereof upon the upper side of the ledge 12. A layer of fine silk cloth, gauze or the like, 60 such as indicated at 14, is then disposed upon the upper surface of the filter or screen 13. A ring 15 is then disposed upon the upper surface of the filter 14 and the peripheral edges of the filter 13 are then bent 65 inwardly over and about the upper exposed surface thereof in the manner shown in Figure 3 of the drawings to maintain the entire strainer or filter in position for use.

As noted in Figure 3, the rims 10 and 11 are provided with registering curved portions 16 upon diametrically opposite sides thereof and upon their uppermost peripheries to prevent injury to the nostrils and distortion of the natural shape of the nose. 70 The invention may be constructed in such manner, however, so that the appearances of people having flat noses will be materially improved.

In Figure 4 of the drawings I have shown 75 a modified form of my invention, which conforms to a great extent to the preferred form save for the fact that the outer rim is made wider than the inner rim, as employed in the preferred form, is deleted. The latter form may be employed to a useful effect within the nostrils of persons having sensitive and irritated nasal channels as the single rim is more elastic and resilient than two rims and will compensate with the nostrils as same are flared and contracted during the natural breathing of the wearer.

The invention is susceptible of various changes in its form, proportions and minor details of construction, and the right is here- 100

in reserved to make such changes as properly fall within the scope of the appended claim.

Having described the invention, what is claimed is:—

A nostril insert comprising an oval-shaped rim having portions removed upon diametrically opposite sides and inner periphery thereof to prevent distortion of the natural shape of the nostrils, an annular flange inwardly directed from the other peripheral edge, a filter having upper and lower layers disposed within the rim, a ring reposing upon the upper surface of the upper layer and forcing the lower layer against said flange, and the lower layer of the filter having the side edges thereof extending peripherally of the upper layer and ring and reposing against the upper surface of the latter.

In testimony whereof I affix my signature.

FERNANDO FORÉS.
